UNITED STATES PATENT OFFICE.

JASMIN PIERRE BERGERON, OF PASADENA, CALIFORNIA.

ROTARY INTERNAL-COMBUSTION ENGINE.

1,272,698.

Specification of Letters Patent.

Patented July 16, 1918.

Application filed June 18, 1917. Serial No. 175,262.

To all whom it may concern:

Be it known that I, JASMIN PIERRE BERGERON, a citizen of the United States, residing at Pasadena, in the county of Los Angeles, State of California, have invented 5 certain new and useful Improvements in Rotary Internal-Combustion Engines, of which the following is a specification.

This invention has to do with improvements 10 in explosion engines, and pertains particularly to that type of engine wherein the impact of the exploded mixture is directed toward and acts upon a rotative member.

15 The principal object of my invention is to provide a motor of inexpensive type, combining simplicity of construction, ease and economy of operation, with great efficiency and power, having no delicate or intricate mechanism, and adaptable to any motor purpose from the smallest to the largest of stationary power requirements, for moving vehicles of all kinds, for aeroplanes, ocean going vessels, etc.

20 It will be noticed that as shown herein, this engine is a unit plant: the engine is susceptible to multiple expansion of these units on one shaft, each unit acting independently of any of the others, yet all adding 25 to the propulsive force. One of the important features of my invention is the provision of a combustion chamber separate from the compression cylinder, and into which the gas mixture is forced from the cylinder and retained in dissociation therefrom during explosion. In the usual type 30 of reciprocating motor and in many rotary explosion engines, the action of the piston is to compress the gas mixture in the cylinder wherein explosion occurs. In my motor no explosion takes place in the cylinder and, therefore, the crank and piston are not strained and racked by violent 35 concussion, and shocks in imparting movement 40 to the shaft. The only purpose for which I use the pistons and cylinders is for compressing the mixture and by their aid forcing the explosive mixture into the separate combustion chamber in which explosion occurs. From this chamber the impact force 45 of the exploded mixture is directed outwardly through a discharge opening and against the rotative member. It follows 50 that as there is no dead center incident to explosive action, as occurs in reciprocating 55

engines, the dangers of back-firing are eliminated; and, as the movements are in one continuous direction without the pound or jerk of reciprocating parts, the action is necessarily smooth and silent. 60

A special feature of novelty is the closure band, whereby all discharge openings are held securely closed until the impact member is in proper place for the ignition of the charge: also the provision for allowing 65 full expansion of all metal parts without any binding or restriction of movement.

A further feature of novelty is the method 70 shown for overcoming the action of centrifugal force in its effort to throw the closure band outwardly from contact with the discharge openings, and to convert this undesired centrifugal action into a beneficial retaining force.

A still further improvement is the method 75 of automatically opening and closing the air supply as required when the motor is in action and when stopped. It is to be noted that as the action of the air compressor is continuous, the excess supply of air may be 80 stored in tanks for other uses such as filling tires, braking and for operating self-starters, etc.

Another novel feature consists in regulating 85 the number of explosions by controlling the admission of the gas mixture to such cylinders as desired.

I have illustrated an embodiment of my invention in the accompanying drawings, in which— 90

Figure 1 is a side elevation, one half being shown in section as seen on the line 1—1 of Fig. 2. Fig. 2 is a vertical section as seen on the line 2—2 of Fig. 1. Fig. 3 is a view of a disk valve detail as seen on the line 95 3—3 of Fig. 2. Fig. 4 is a longitudinal section through one form of my valveless combustion chamber. Fig. 5 is a view as seen on the line 5—5 of Fig. 4. Fig. 6 is an enlarged fragmentary view showing the 100 disk valve structure as shown in Fig. 2. Fig. 7 is an enlarged longitudinal section through a piston rod. Fig. 8 is a sectional view of the manually operative gas closures or valves. 109

Referring more particularly to the drawings, a stationary member is indicated as a whole by 10. Stationary member 10 is provided with a series of four cylinders 11, 12, 13 and 14 preferably cast *en bloc*. Within 110

each cylinder is a reciprocating piston 15. Each of the pistons 15 is connected by a piston rod 16 to a crank 17 which is formed on the shaft 18. On each rotation of the 5 shaft 18, the crank 17 reciprocates the piston rods 16, and thereby causes the pistons 15 to reciprocate in the cylinders in exact sequence. As shown, in cylinder 11, the 10 stroke of the piston rod has brought the piston head and cylinder head in contact; the piston in cylinder 12 is completing the compression stroke; the piston in cylinder 13 has completed the suction stroke and is about to begin the compression stroke. The 15 position of the piston in cylinder 14 is not shown, but it follows that it is moving outwardly on the suction stroke and drawing in a charge of the gas mixture.

The combustion chambers 19 may be cast ^{on bloc} integrally with the stationary member 10, or may be separately made and assembled as shown in the drawing, the usual gas tight joint being provided to prevent leakage. For the purpose of assisting in 25 cooling the combustion chambers, I have shown them provided with cooling pins 20, driven into constricted bores. However, cooling flanges may be cast integral with the combustion chambers. In my construction 30 an air current is blown over the combustion chambers by a fan later described.

A rotatable shell 21 is preferably cast as one piece with arms 22, which latter are provided with extensions 23 to form fan 35 blades. These fan blades blow a current of air over the combustion chambers. The arms are formed integral with a hub 24, which is shrunk on or otherwise suitably secured to the shaft 18. The casing 21 revolves free from any contact with stationary 40 member 10, but carries within it the element 25, which may be described as an impact member, and the closure band 26, the latter being preferably made in sections to allow 45 for temperature expansion. The band and the impact member are held in contact with the periphery of the stationary member 10, and revolve around it on a narrow track-way 27, and move over the discharge openings 50 of the combustion chambers. The frictional binding is limited to these small surfaces and offers little resistance to the revolution of the shell. The closure band 26 is intended to close the discharge openings 55 of the combustion chambers during the compression of the gas mixture in the combustion chamber.

To retain the closure band in close contact with the discharge openings, springs 60 28 are employed. Springs 28 surround posts 29 formed on the closure band, and are interposed between shell 21 and the closure band. Posts 29 extend through apertures formed in the shell 21 and project beyond 65 the surface thereof. As the closure of the

combustion chambers during the compression must be positive to retain the closure band in intimate contact at the great speed of the rotatable member in consequence of the development of centrifugal force which 70 at times may exceed the resisting effort of the spring 28, I employ a centrifugally operated mechanism. This mechanism comprises pivoted levers 30 having one arm resting upon the ends of posts 29 and a weight 31 75 disposed upon the other arm. As the speed increases the weight 31 tends to move outwardly with greater effort and exert a greater pressure on the posts 29 through the medium of levers 30. In this manner I employ the centrifugal action to depress the posts 29, so that an equal pressure is constantly bearing on the closure band, and the speed automatically and selectively determines the necessary pressure on the closure 80 band. The weights 31 are slidably movable on the lever 30 to allow adjustment against a too great frictional binding of the closure band; when such point has been determined to produce the proper pressure, the weights 85 are permanently fixed against accidental displacement by bolts 32.

It will be noted that the shell 21 is in effect a fly-wheel and that in heavy engines an extension thereof to any desired 95 extent may be provided. Loosely held in a recess formed within the shell 21 is the impact member 25 which is somewhat smaller in dimensions than the recess to allow for temperature expansion. Its forward abutment is in direct close contact with the casing 21 or the forward wall of the recess, so that the impact force of the explosion is communicated to the rotative member exactly as though it were a part thereof. The 100 lower face of the impact member rides over the discharge openings of the combustion chambers and is cut with a transverse series of serrations 33 against which the impact force is directed. These serrations are 105 preferably formed fully within the impact member and riding over the discharge openings of the combustion chambers form a confined space against which the force or impact of the exploded mixture is imparted in full. 110

At 34 is shown an air compressor acted upon by a crank 35 of adjustable length and forming a part of shaft 18. The compressor 34 feeds air to an air storage tank 36, by means of a pipe 37, the usual puppet 115 valve being employed to retain the compressed air therein. If an excess of the required pressure is developed in the storage tank, a regulating valve may be employed to dispose of the excess pressure. From 120 the storage tank the compressed air passes into a pipe 38 circling the outer side of stationary member 10, the method of its use being explained later.

The gas mixture from the carburetor 130

may be admitted into the cylinders by any of the usual methods, but I employ my novel disk means, as shown in Figs. 1, 2, 3 and 6. The rotation of the shaft 18 revolves the bevel gear 39 which in turn rotates four smaller bevel gears 40 and the spur gears 41 and 42 to effect a rotation of the disk valve 43 in exact ratio—each revolution of the shaft through the train of 10 gears causing one revolution of the disk 43. Disk 43 is rotatably seated in a recess formed on the inner face of the cylinder head 44 so as to be held by the spring 45 in close contact and to be of even thickness 15 with the depth of the recess in which it is seated, so that no pocket may be formed to retain gas mixture, nor projection to prevent the piston head from forming an intimate contact with the inner space of the 20 cylinder head.

The disk 43 rotates continuously in one direction and has one opening 46 bored through it, which in its revolution registers in turn with a port from pipe 47 to admit 25 a charge of gas mixture into the cylinder, closes the port by presenting its solid part thereto to allow for compression and ignition, and continues its rotation until its opening registers with the air port from 30 pipe 38 for scavenging with the compressed air. As shown in Fig. 3, the pipes 38 and 47 end in ports formed on the inner face of the cylinder head, the ports extending a distance which is gaged to the need of 35 time of admission of the compressed air and the mixture; the mixture requiring a longer time for the suction thereof into the cylinder, having a greater length of port of the air pipe which supplies air under 40 pressure. The opening 46 in the disk 43, passing under these ports, automatically and for the proper period allows the passage through it of the mixture and of the air.

45 The air in its compressed form is maintained at a uniform pressure in pipe 38 which is supplied from the storage tank 36. When the engine is not in operation, if an opening in a disk valve should register with an air port, air would flow from the air tank through the combustion chamber to the exhaust and the storage tank 36 would soon be drained of all its air. To prevent this escape, I use a control valve 48, 50 Fig. 2, in the main air pipe, which normally is closed when the shaft is not rotating and is open during rotation. This controllable action is obtained by means of a governor 49 actuated by pulley wheels from the main 55 shaft 18. The governor arms 50 are normally closed when the engine is not running and the control valve, therefore, is held upon its seat at such time, thereby shutting off the supply of air to pipe 38. 60 When shaft 18 rotates, the arms 50 fly out-

wardly and draw the control valve from its seat thereby connecting the storage tank 36 and the main air pipe 38.

The cylinders 11, 12, 13 and 14 may be of lighter and cheaper material than in the 70 ordinary type of reciprocating engine in which explosion occurs in the cylinders. As the purpose of the cylinder in my engine is simply to compress the gas mixture, their weight may be greatly reduced. 75

Between the cylinders and the combustion chamber an admission port 51 is formed in the cylinder walls. Controlling this port is a valve 52 which is automatically acted upon by difference of pressure to open and 80 close the port as required, the action of which will be later described.

The packing of pistons 15 of any suitable material to form closure against compression. In one form of the lightest type of 85 my motor, as shown in Figs. 4 and 5, the closure of the port into the combustion chamber is effected by the aid of the piston head without the interposition of any valve. In such types the upper piston ring is of 90 metal, but the very small area subject to the explosion impact is of no great consequence. In this type of motor as shown in Fig. 5, the port 51 is placed at one side of the combustion chamber, whereby at each impact a slight turning of the piston head presents a new surface, thereby preventing wear or overheating of the piston ring. In the type of motor in which I use the 95 puppet valve 51', the material for the piston 100 ring may be of other composition than metal.

The piston head and the cylinder head must be in intimate contact at the conclusion of the compression of the gas mixture, and to avoid the clashing of the surfaces, I employ two means, one of which is a composition covering 53 on the piston head of slightly yielding material which acts as a buffer therebetween. The other means resides in an accurate adjustment of the piston rod 16. In Fig. 7, the preferred form of rod construction is shown. The upper part of the rod has a ball 54 fitted into a socket 55 which may be tightened by a bolt 110 and nut or other suitable means to allow a free movement of the ball in the socket and yet be firm enough to prevent looseness of action. The stem 56 is screwed into the sleeve 57 to allow adjustment of the piston. The sleeve 57 has slidably mounted therein the stem 58 and is limited in its movement by the pin 59 which is fixed to the stem 58 and which extends through the slot 60. Enclosed within the sleeve is a spring 61, which 115 maintains the stem 58 fully extended, and the spring tension is of such strength as to be inoperative against the compression force. In practice the piston head is brought in 120 close contact with the cylinder head by turn- 125 130

ing the crank shaft until the piston head is at its fullest extension; the stem 56 is then turned to screw in or out the sleeve 57 until proper adjustment is made, the set 5 screws 62 being then tightened to retain the adjustment when made. Should the surfaces meet with greater impact than necessary, the spring 61 will then act as a resilient buffer.

10 I will now describe the action of the motor in operation. The shaft 18 being rotated, the piston rods 16 disposed on the crank 17 are drawn in and out of the cylinder in exact sequence. In Fig. 1 the piston in cylinder 11 has just completed contact with its cylinder head. The impact member 25 is in exact position for the firing charge which has been ignited by the brush contact 63 mounted on the revoluble shell 21, making contact with the contact 64 mounted upon the periphery of the stationary member 10. These members are electrically connected with the battery 65, which may be of the usual construction. The contact 64 may be grounded while contact 63 is insulated. The spring contact 63 being electrically connected with contact 64 completes a circuit through spark plug 66 and produces a spark in the combustion chamber 19. Each of the other combustion chambers is provided with a similar ignition circuit. Any other suitable ignition system may be used.

35 The piston head in cylinder 11 has now begun to move outwardly and the port 46 in disk 43 now being in register with the air ports allows compressed air to flow from the pipe 38 into the cylinder and pass over the piston head through port 51, pushing 40 back as it does so the valve 52, whence it passes through combustion chamber 19; by this time the impact member 25 has advanced and its serrations 33 open a way for the escape of the air, turning the dead gases 45 into the trough 67, which is connected with the exhaust pipe surrounding the stationary member and whose outer end is shown at 68.

50 The piston head has by this time moved the short distance to the lower edge of port 51, the air ports closing and the gas ports registering with the bore 46 in disk 43. The movement of the piston draws in the gas mixture and by suction closes the valve 52 until the piston has reached the full extent 55 of its stroke, whereupon the gas port closes and the compression stroke of the piston takes place. As the piston head reaches contact with the cylinder, the compressed mixture has been fully forced into 60 the combustion chamber and it is evident that all pressure against the valve 52 on the cylinder side has reverted to full pressure back of it in the combustion chamber, it, therefore, is pressed into its seat. At the 65 moment of contact between the cylinder

head and piston head, the brush contact fires the charge.

The shaft action continuing, the piston in cylinder 12 closes, the impact member advances to its firing point for said cylinder, 70 explosion occurs, and so on in regular succession to cylinders 13 and 14 and again to cylinder 11, the cycle again being repeated.

At times in the operation of light loads, it may not be desirable to use the full force 75 of the engine, in which case the inlet of gas mixture to one or more cylinders may be shut off. To do this I employ manually operated gas valves which are interposed in the main pipe 47 and are indicated by 69 80 and 70. Referring particularly to Fig. 8 the valve shown is of the plug type having three ways, and the valve casing having an opening to the atmosphere. In the position valve 69 is shown, the gas is admitted to 85 the cylinder. In the position shown by valve 70, the cylinder is connected to the atmosphere and gas mixture is cut off. It is evident that if the gas valves were of the ordinary type, the closure of the gas mixture 90 supply pipe would cause a strain on the piston rod in operating against the vacuum that would be formed in the cylinders. This is overcome by forming a way in the valve which is connected to the atmosphere when 95 the gas mixture is shut off. The form above here shown is for a stationary engine, but in vehicles or aeroplanes, a series of handles on the instrument board may be provided to control the valves.

100 The fan blades 23 formed on the arm 22 may in general be relied upon to give full air cooling, but I may use on some forms of engines an auxiliary fan 71. This fan is mounted on the shaft 18 and has a greater 105 speed than the shaft by reason of the pulleys 72, 73, 74 and 75.

110 It will be noticed that an economical feature of operation is that the usual oil in the cylinders is not required and that I, therefore, eliminate the complications of oil pump, splash system, or other method incident to the use of oil. Another advantage is that the gases exploded clear of oil are freer of carbon. The motor is cooled by air permitting a further reduction in weight, and reduction in complicated structure and cost of manufacture is effected.

115 What I claim is:—

1. A rotary internal combustion engine 120 comprising the combination of a combustion chamber, means for supplying a charge thereto, said chamber provided with a discharge outlet, means for igniting the charge in said combustion chamber, a rotatable 125 shell surrounding said chamber, a closure band in said shell, and an impact member movable abreast of said discharge outlet for being impelled by the discharge of gases from said combustion chamber, said impact 130

member being movably mounted in said shell to allow for temperature changes.

2. A rotary internal combustion engine comprising the combination of a combustion chamber having a discharge outlet, a rotatable shell surrounding said chamber, a closure band in said shell, a compressor independent of and communicating with said combustion chamber, said compressor being 10 for compressing a charge of an explosive mixture and supplying the same to said combustion chamber, means for igniting the charge in said combustion chamber, and an impact member movable abreast of said discharge outlet, said impact member being movably mounted in said shell to allow for temperature changes.

3. A rotary internal combustion engine comprising the combination of a stationary member provided with a combustion chamber having a discharge outlet, a compressor for compressing a charge and feeding the same to said combustion chamber, a rotatable shell, an impact member movable 25 abreast of said discharge outlet, said impact member being movably mounted in said shell to allow for temperature changes, ignition means for the charge in said combustion chamber, means for closing said discharge outlet prior to ignition, and means to cut off communication between said compressor and said combustion chamber while ignition takes place.

4. A rotary internal combustion engine comprising the combination of a stationary member provided with a combustion chamber having a discharge outlet, means for supplying a compressed explosive mixture to said chamber, a rotatable shell, an impact member movable abreast of said outlet, said impact member being movably mounted in said shell to allow for temperature changes, means for igniting the contents of said chamber, and means for admitting compressed air to said combustion chamber for expelling the burnt gases therefrom.

5. A rotary internal combustion engine comprising the combination of a combustion member having a combustion chamber provided with a discharge outlet, ignition means for the charge in said combustion chamber, an impact member movable abreast of said discharge outlet, a compressor for compressing and supplying an explosive mixture to said combustion chamber, a source of compressed air, a source of fuel, valve means for connecting said source of compressed air and said source of fuel to said compressor, said valve means admitting 55 compressed air to said compressor and therethrough to said combustion chamber after ignition of the mixture and while said impact member is abreast of said discharge outlet, and closure means to maintain said 60 discharge outlet closed while said impact

surfaces are not abreast of said discharge openings.

6. A rotary internal combustion engine comprising the combination of a stationary member having a combustion chamber provided with a discharge outlet on its periphery, ignition means for the charge in said combustion chamber, a rotary member having an impact member movable abreast of said discharge outlet, a compressor for 70 compressing and supplying an explosive mixture to said combustion chamber, a source of compressed air, a source of fuel, valve means for connecting said source of compressed air and said source of fuel to 75 said compressor, said valve means admitting compressed air to said compressor and therethrough to said combustion chamber after ignition of the charge and while said impact member is abreast of said discharge outlet, 80 and a closure band revolvably disposed over the periphery of said stationary member and fixed to said rotatable member, said closure band maintaining said discharge outlet closed while said impact member is not 85 abreast of said discharge outlet.

7. A rotary internal combustion engine comprising the combination of a stationary member having a combustion chamber provided with a discharge outlet on its periphery, ignition means for the charge in said combustion chamber, a rotary member having an impact member movable abreast of said discharge outlet, a compressor for compressing and supplying an explosive mixture to 90 said combustion chamber, a source of compressed air, a source of fuel, valve means for connecting said source of compressed air and said source of fuel to 95 said compressor, said valve means admitting compressed air to 100 said compressor and therethrough to said combustion chamber after ignition of the charge and while said impact member is abreast of said discharge outlet, a closure band revolvably disposed over the periphery of 105 said stationary member and fixed to said rotatable member, said closure band maintaining said discharge outlet closed while said impact member is not abreast of said 110 discharge outlet, and centrifugally operated means to force said band toward the periphery of 115 said stationary member.

8. A rotary internal combustion engine comprising the combination of a stationary member having a combustion chamber provided with a discharge outlet on its periphery, ignition means for the charge in said combustion chamber, a rotary member having an impact member movable abreast of said discharge outlet, a compressor for compressing and supplying an explosive mixture to said combustion chamber, a source of compressed air, a source of fuel, valve means for connecting said source of compressed air and said source of fuel to 120 said compressor, said 125 valve means admitting compressed air to said compressor and therethrough to said combustion chamber after ignition of the mixture and while said impact member is abreast of said discharge outlet, and closure means to maintain said discharge outlet closed while said impact

- valve means admitting compressed air to said compressor and therethrough to said combustion chamber after ignition of the charge and while said impact member is 5 abreast of said discharge outlet, a closure band revolubly disposed over the periphery of said stationary member and fixed to said rotatable member, said closure band maintaining said discharge outlet closed while 10 said impact member is not abreast of said outlet, a lever pivotally mounted on said rotatable member, one arm of said lever weighted and the other arm linked to said band so as to transmit the centrifugal force 15 into pressure for holding said band on its seat.
9. The combination of a revoluble band which is radially movable, a rotatable member for revolving said band, a lever pivot- 20 ally mounted on said rotatable member, one arm of said lever being weighted and the other arm linked to said band so as to transmit the centrifugal force into pressure for holding said band on its seat.
- 25 10. A rotary internal combustion engine comprising a stationary member, a radially disposed cylinder therein, a piston reciprocating in said cylinder, a rotatable crank, a piston rod connecting said crank and said piston, a combustion chamber communicating with said cylinder but independent thereof, said combustion chamber, a discharge outlet, a rotatable member having an impact member movable abreast of said dis- 30 charge outlet, said impact member being movably mounted in said rotatable member to allow for temperature changes, and ignition means for the charge in said combustion chamber.
- 35 11. A rotary internal combustion engine comprising the combination of a stationary member, a radially disposed cylinder therein, a piston reciprocating in said cylinder, a rotatable crank, a piston rod connecting 40 said crank and said piston, a combustion chamber communicating with said cylinder but independent thereof, said combustion chamber having a discharge outlet, a rotatable member, an impact member movable 45 abreast of said discharge opening, said impact member being movably mounted in said rotatable member to allow for temperature changes, ignition means for the charge in said combustion chamber, and a closure 50 member disposed to close said discharge outlet while said impact member is not abreast thereof.
- 55 12. A rotary internal combustion engine comprising the combination of a stationary member, a radially disposed cylinder therein, a piston reciprocating in said cylinder, a rotatable crank, a piston rod connecting said crank and said piston, a combustion chamber communicating with said cylinder but 60 independent thereof, said combustion chamber having a discharge outlet, a rotatable member having an impact member movable abreast of said discharge outlet, ignition means for the charge in said combustion chamber, a closure member disposed to close said discharge outlet while said impact member is not abreast thereof, a source of compressed air, a source of fuel, valve means to control the supply of compressed air and fuel to said cylinder, said valve means placing the source of compressed air in communication with said cylinder before said closure member closes said discharge outlet, thereby scavenging the combustion chamber. 65
- 70 13. A rotary internal combustion engine comprising the combination of a stationary member, a radially disposed cylinder therein, a piston reciprocating in said cylinder, a rotatable crank, a piston rod connecting said crank and said piston, a combustion chamber communicating with said cylinder but independent thereof, said combustion chamber having a discharge outlet, a rotatable member having an impact member movable abreast of said discharge outlet, ignition means for the charge in said combustion chamber, a closure band revolubly disposed over the periphery of said stationary member and fixed to said rotatable member, said closure band maintaining said discharge outlet closed while said impact member is not abreast of said opening. 75
- 80 14. A rotary internal combustion engine comprising the combination of a stationary member, a radially disposed cylinder therein, a piston reciprocating in said cylinder, a rotatable crank, a piston rod connecting said crank and said piston, a combustion chamber communicating with said cylinder but independent thereof, said combustion chamber having a discharge outlet, a rotatable member having an impact member movable abreast of said discharge outlet, ignition means for the charge in said combustion chamber, a closure band revolubly disposed over the periphery of said stationary member and fixed to said rotatable member, said closure band maintaining said discharge outlet closed while said impact member is not abreast of said opening. 85
- 90 15. A rotary internal combustion engine comprising the combination of a stationary member, a radially disposed cylinder therein, a piston reciprocating in said cylinder, a rotatable crank, a piston rod connecting said crank and said piston, a combustion chamber communicating with said cylinder but independent thereof, said combustion chamber having a discharge outlet, a rotatable member having an impact member movable abreast of said discharge outlet, ignition means for the charge in said combustion chamber, a closure band revolubly disposed over the periphery of said stationary member and fixed to said rotatable member, said closure band maintaining said discharge outlet closed while said impact member is not abreast of said opening. 95
- 100 16. A rotary internal combustion engine comprising the combination of a stationary member, a radially disposed cylinder therein, a piston reciprocating in said cylinder, a rotatable crank, a piston rod connecting said crank and said piston, a combustion chamber communicating with said cylinder but independent thereof, said combustion chamber having a discharge outlet, a rotatable member having an impact member movable abreast of said discharge outlet, ignition means for the charge in said combustion chamber, a closure band revolubly disposed over the periphery of said stationary member and fixed to said rotatable member, said closure band maintaining said discharge outlet closed while said impact member is not abreast of said opening. 105
- 110 17. A rotary internal combustion engine comprising the combination of a stationary member, a radially disposed cylinder therein, a piston reciprocating in said cylinder, a rotatable crank, a piston rod connecting said crank and said piston, a combustion chamber communicating with said cylinder but independent thereof, said combustion chamber having a discharge outlet, a rotatable member having an impact member movable abreast of said discharge outlet, ignition means for the charge in said combustion chamber, a closure band revolubly disposed over the periphery of said stationary member and fixed to said rotatable member, said closure band maintaining said discharge outlet closed while said impact member is not abreast of said opening. 115
- 115 18. A rotary internal combustion engine comprising the combination of a stationary member, a radially disposed cylinder therein, a piston reciprocating in said cylinder, a rotatable crank, a piston rod connecting said crank and said piston, a combustion chamber communicating with said cylinder but independent thereof, said combustion chamber having a discharge outlet, a rotatable member having an impact member movable abreast of said discharge outlet, ignition means for the charge in said combustion chamber, a closure band revolubly disposed over the periphery of said stationary member and fixed to said rotatable member, said closure band maintaining said discharge outlet closed while said impact member is not abreast of said opening. 120
- 120 19. A rotary internal combustion engine comprising the combination of a stationary member, a radially disposed cylinder therein, a piston reciprocating in said cylinder, a rotatable crank, a piston rod connecting said crank and said piston, a combustion chamber communicating with said cylinder but independent thereof, said combustion chamber having a discharge outlet, a rotatable member having an impact member movable abreast of said discharge outlet, ignition means for the charge in said combustion chamber, a closure band revolubly disposed over the periphery of said stationary member and fixed to said rotatable member, said closure band maintaining said discharge outlet closed while said impact member is not abreast of said opening. 125
- 125 20. A rotary internal combustion engine comprising the combination of a stationary member, a radially disposed cylinder therein, a piston reciprocating in said cylinder, a rotatable crank, a piston rod connecting said crank and said piston, a combustion chamber communicating with said cylinder but independent thereof, said combustion chamber having a discharge outlet, a rotatable member having an impact member movable abreast of said discharge outlet, ignition means for the charge in said combustion chamber, a closure band revolubly disposed over the periphery of said stationary member and fixed to said rotatable member, said closure band maintaining said discharge outlet closed while said impact member is not abreast of said opening. 130

bustion chamber, a closure band revolvably disposed over the periphery of said stationary member and fixed to said rotatable member, said closure band maintaining said discharge outlet closed while said impact member is not abreast of said opening, a lever pivotally mounted on said rotatable member one arm of said lever being weighted and the other arm linked to said band, so as 10 to transmit the centrifugal force into pressure for holding said band on its seat.

16. A rotary internal combustion engine comprising the combination of a stationary member, a radially disposed cylinder therein, a piston reciprocating in said cylinder, a rotatable crank, a piston rod connecting said crank and said piston, a combustion chamber communicating with said cylinder but independent thereof, said combustion 20 chamber having a discharge outlet, a rotatable member having an impact member movable abreast of said discharge outlet, ignition means for the charge in said combustion chamber, a closure band revolvably disposed over the periphery of said stationary member and fixed to said rotatable member, said closure band maintaining said discharge outlet closed while said impact member is not abreast of said opening, a source 25 of compressed air, a source of fuel, valve means to control the supply of compressed air and fuel to said cylinder, said valve means placing the source of compressed air in communication with said cylinder before 30 said closure member closes said discharge outlet, thereby scavenging the cylinder.

17. A rotary internal combustion engine comprising the combination of a stationary member, a radially disposed cylinder therein, a piston reciprocating in said cylinder, a rotatable crank, a piston rod connecting said crank and said piston, a combustion chamber communicating with said cylinder but independent thereof, said combustion chamber having a discharge outlet, a rotatable member having an impact member movable abreast of said discharge outlet, ignition means for the charge in said combustion chamber, a closure band revolvably disposed

over the periphery of said stationary member 60 and fixed to said rotatable member, said closure band maintaining said discharge outlet closed while said impact member is not abreast of said outlet, centrifugally operated means to force said band toward the periphery of said stationary member, a source of compressed air, a source of fuel, valve means to control the supply of compressed air and fuel to said cylinder, said valve means placing the source of compressed air in communication 65 with said cylinder before said closure member closes said discharge outlet thereby scavenging the cylinder.

18. A rotary internal combustion engine comprising the combination of a stationary member, a radially disposed cylinder therein, a piston reciprocating in said cylinder, a rotatable crank, a piston rod connecting said crank and said piston, a combustion chamber communicating with said cylinder but independent thereof, said combustion chamber having a discharge outlet, a rotatable member having an impact member movable abreast of said discharge outlet, ignition means for the charge in said combustion 75 chamber, a closure band revolvably disposed over the periphery of said stationary member and fixed to said rotatable member, said closure band maintaining said discharge outlet closed while said impact member is 80 not abreast of said outlet, a lever pivotally mounted on said rotatable member, one arm of said lever being weighted and the other arm linked to said band so as to transmit the centrifugal force into pressure for holding 85 said band on its seat, a source of compressed air, a source of fuel, valve means to control the supply of compressed air and fuel to said cylinder, said valve means placing the source of compressed air in communication 90 with said cylinder before said closure member closes said discharge outlet, thereby scavenging the cylinder.

In witness that I claim the foregoing I have hereunto subscribed my name this 7th 95 day of June, 1917.

JASMIN PIERRE BERGERON.
